UNITED STATES PATENT OFFICE.

FRED FOX, OF LIMA, OHIO.

AUTOMOBILE SIGNAL.

Application filed August 15, 1921, Serial No. 492,442. Renewed March 22, 1923.

To all whom it may concern:

Be it known that I, FRED FOX, a citizen of the United States, residing at Lima, in the county of Allen, State of Ohio, have 5 invented certain new and useful Improvements in Automobile Signals; and I do hereby declare the following to be a full, clear, and exact description of the invention, such as will enable others skilled in 10 the art to which it appertains to make and use the same.

This invention relates to new and useful improvements in signals and particularly to automobile signals.

15 One object of the invention is to provide a signal which is simple in construction, easy to operate, and which can be readily applied to automobiles now in use.

Another object is to provide a device of 20 this character which arranged to be normally held in withdrawn position against action of spring means which will project the signal.

Other objects and advantages will be apparent from the following description when taken in connection with the accompanying drawing.

In the drawing:

Figure 1 is an elevation of the improved 25 automobile signal.

Figure 2 is a top plan view of the same.

Figure 3 is a longitudinal central sectional view through the device, on the line 3—3 of Fig. 1.

35 Figure 4 is an elevation of the device the rear wall of the casing being removed.

Referring particularly to the accompanying drawing, there is shown a casing having a rear removable wall 11, the casing as a 40 whole being represented by the numeral 10. In the lower portion of the outer end of the casing there is formed a depending enlargement 12 in which is disposed the motor spring 13, having its inner end secured to the shaft 14 which is carried by 45 the casing. Extending longitudinally in the casing for slidable movement, is the signal arm 15. In one side of the inner end portion of the arm 15 there is formed a recess 50 16 for the reception and retention of the outer end of the spring 13, said spring normally urging the arm into extended position from the outer end of the casing. Secured to the rear face of the inner end 55 of the arm 15 is a metal plate 17, the outer

edge of which is disposed adjacent a recess 18 formed in the arm, said recess being arranged to receive the inner end of the spring 13, when the arm is in its innermost position. In the other end of the casing there is mounted a grooved wheel 20, and engaged around this wheel, with one end secured to the inner end of the arm 15, is a cable or cord 21. Secured to the rear face of the pulley carried end of the 60 casing is a yoke 22, and slidable through the transverse portion of the yoke is the before-mentioned bolt 19, the coil spring 23 encircling the bolt between the said member of the yoke and the nut 24, which is engaged on 65 the bolt adjacent its other end. The nut 24 bears against the rear wall of the casing and is adjustable to permit a sufficient portion of the headed end of the bolt to project rearwardly of the transverse portion of the yoke 22, to grasp the same and withdraw the bolt from engagement with the metal plate 17, whereupon the motor 70 spring 13 will exert force to project the signal arm 15 into signaling position 75 through the outer end of the casing. The cord or cable 21 extends through an opening 25 in one end of the transverse portion of the yoke 22, and is provided with a hand grip 26, which is grasped by the operator 80 to pull the arm 15 into the casing. When the arm 15 is thus pulled into the casing the spring 13 engages with the plate 17 and retains the arm thus withdrawn 85 into inoperative position. When the operator desires to extend the signal arm from 90 the casing he simply pulls the bolt 19 so that its inner end will be disengaged from the plate 17, when the motor spring 13 will project the arm through the end of the 95 casing.

In the outer end of the arm there is mounted an electric lamp 27, the wires 28 from which extend longitudinally within the arm and are connected respectively with a contact plate 29, mounted on the inner face of the arm, and to a stationary contact plate 30 mounted on the inner face of the front wall of the casing. Thus, when the arm 15 is projected into signaling position, the contact plates 29 and 30 engage each other to complete a circuit, for lighting the lamp 27, and when withdrawn into the casing the circuit is broken, as will be readily apparent 100 from the drawing. Wires 31 extend from 105 110

the contact plates 29 and 30 to a source of electric current not shown, but which may be the ordinary lighting circuit of the automobile.

5 Suitable brackets 32 are provided for attaching the casing to the dashboard of the automobile, in position for projection of the arm 15 from the side of the automobile, to be seen by the drivers of other vehicles 10 from the front or rear.

What is claimed is:

1. A direction signal comprising an elongated casing having a recess in one side, a signal arm movable longitudinally in the 15 casing, releasable means engaged with the arm for holding the arm within the casing, a drum mounted in the recess, and a flat motor spring secured to and wound on the drum and having its other end extending 20 longitudinally within the casing, and secured to the inner end of the arm to normally

urge the arm outwardly through the end of the casing.

2. A direction signal including an elongated casing having a recess in one side, 25 a signal arm slideable in the casing and arranged to be projected through one end, a flat motor spring mounted in the recess and having one end secured to the inner end of the arm, the inner end of the arm 30 having an opening, a spring pressed plunger mounted on the inner end of the casing and engaging in the opening of the signal arm, and a flexible element secured to the inner 35 end of the arm for drawing the arm inwardly into engagement with the plunger.

In testimony whereof, I affix my signature, in the presence of two witnesses.

FRED FOX.

Witnesses:

T. R. HAMILTON,
AUGUSTA RIDENOUR.
